UNITED STATES PATENT OFFICE.

JAMES R. QUINLAN, OF PLEASANT RIDGE, MICHIGAN.

INTERNAL-COMBUSTION ENGINE.

Application filed May 8, 1922. Serial No. 559,129.

To all whom it may concern:

Be it known that I, JAMES R. QUINLAN, a citizen of the United States, and residing in the village of Pleasant Ridge, in the 5 county of Oakland and State of Michigan, have invented new and useful Improvements in an Internal-Combustion Engine, of which the following is a specification.

The object of my invention is to provide 10 improvements in an internal combustion engine, of simple, durable, and inexpensive construction.

A further object of my invention is to provide an internal combustion engine having a prime mover such, for instance, as an electric motor associated therewith, for the purpose of starting the engine, and to provide, in connection with such motor, means for automatically engaging and disengaging 20 it with some portion of the engine when the starting motor is actuated and the engine running under its own power respectively.

A further object of my invention is to provide an engaging device of the type described, which may be attached to the motor shaft as an assembly in position to co-act with the teeth on a moving part of the engine such, for instance, as the fly wheel, the engaging device being so arranged that when 30 current is supplied to the motor then that the engaging device will automatically engage the teeth mentioned, but when the engine starts running under its own power then the teeth will be disengaged.

A further object of my invention is to provide such an engaging device with means for automatically moving an engaging pinion along a shaft when the parts associated therewith are rotated, this movement 40 being accomplished by the inertia of the pinion and the functions of the parts associated therewith.

A further object of my invention is to provide means associated with such engaging device and pinion to form a yielding connection between the engaging device and pinion both for the purpose of cushioning the shock of engagement, and also for the 50 purpose of forming an automatic slippage device in case the engine backfires.

A further object of my invention is to provide yielding means for automatically holding the pinion out of engagement with the teeth on the engine when the pinion is 55 in inoperative position.

A further object of my invention is to

provide a novel form of cam device for utilizing the inertia of the pinion and parts associated therewith for moving the pinion into and out of engagement. 60

A further object of my invention is to provide an association of parts in connection with the slippage device mentioned and the cam device mentioned whereby movement of the pinion in a direction causing it to engage teeth on the engine, this movement being caused by the cam device, will in turn affect the slippage device to regulate the slippage permitted thereby. In this connection it may be mentioned that 70 this feature is designed for the purpose of eliminating the necessity for adjusting the tension or bearing of the slippage device from time to time.

A further object of my invention is to provide a device wherein the driving pinion will not form a driving connection between the starting motor and engine until the teeth of the pinion are fully engaged with the teeth associated with the engine, so that 80 there may be no undue strain on the teeth of either the pinion or engine.

A further object of my invention is to provide a clutch device of the type known as a "multiple disc clutch" which may be 85 interposed between the engaging pinion and the motor shaft thereby securing the necessary cushioning and slippage between the motor shaft and the engine.

With these and other objects in view, my invention consists in the arrangement, combination, and construction of the various parts of my improved device, as described in the specification, claimed in my claims, and shown in the accompanying drawings, in 95 which:

Figure 1 shows a side elevation of an internal combustion engine having a transmission associated therewith, a starting motor, and an engaging device, parts being broken away to better illustrate the construction.

Figure 2 shows an elevation of the engaging device illustrated in Figure 1, parts thereof being shown in vertical central section to better illustrate the construction. 105

Figure 3 shows an end elevation of the device illustrated in Figure 2.

Figure 4 shows an end view of the engaging device.

Figure 5 shows a sectional view taken on 110 the line 5-5 of Figure 2.

Figures 6, 7, 8, and 9, show detail views

illustrating the construction of the clutch discs used in connection with my improved engaging device.

Figures 10 and 11 show detail views illustrating the construction of an improved washer used in connection with my clutch, and

Figures 12 and 13 are detailed, sectional views illustrating the details of my improved latching device.

Referring to the accompanying drawings, I have used the reference numeral 10 to indicate, generally, the cylinder block of an engine having a crank case 11 and a transmission cover 12; near this transmission cover 12 is an engine fly wheel 13 having teeth 14 thereon whereby the fly wheel may be operatively connected with the starting motor 15 which, in the form here shown, is illustrated 20 as an electric motor. This starting motor 15 has a drive shaft 16 thereon which extends thru a nose 17 into the transmission cover 12, and is designed to carry the engaging device heretofore mentioned. This engaging device 25 is housed in a cover or cap 18 which extends rearwardly from a portion of the transmission housing 12. This engaging device consists of an assembly comprising three main portions—viz an engaging gear or pinion 19, a friction disc clutch housed in the portion 20, and cam devices designated, generally, by the reference numeral 21 which are designed to force the pinion 19 longitudinally along the shaft 16 so that it may either 30 engage with or be disengaged from the teeth 14 of the fly wheel 13. The pinion 19 has bevelled faces 22 at the front or engaging edge of the teeth 23 thereon and is designed to have a running fit on the adjacent portion 40 of the shaft 16 so that it either may slide longitudinally thereon, or rotate thereon. The rear end of the pinion 19 has a contracted portion 24 and between this contracted portion 24 and the teeth 23 there is a 45 laterally extended portion designed to receive lugs 25 which extend inwardly from friction disc members 26. These members are prevented from movement past the teeth 23 by engaging the rear ends of these teeth. 50 If desired, a reinforcing washer 31 of relatively heavy material may be provided as a packing for the disc clutch members to bear against, and at the same time to separate these clutch members from the rear ends of the 55 teeth 23. Mounted for rotary movement on the contracted end of 24 of the pinion 19 is a clutch housing member 28 which has a laterally extending annular flange 29 at its outer edge designed to partially house the clutch 60 discs and to co-act with said discs to hold them from rotation. This rotary movement of the housing 20 relative to the pinion 19 is accomplished by grooving the annular reduced portion 24 of the pinion 19 and then extending one or more screws 27 thru the hous-

ing 20 into the groove in the reduced portion 24 to thereby permit the necessary rotation. A locking wire 60 may be provided if desired to hold these screws from being accidentally displaced, and it will be noted that the annular groove mentioned is of such width, relative to the ends of the screws 27, that sufficient longitudinal movement of the housing 20 relative to the pinion 19 is permitted so that the friction clutch member may be properly engaged and disengaged.

In connection with friction disc clutches it may be here explained that there are usually one set of discs which are held from rotation relative to the shaft, and a second set of discs which alternate with the first set of discs which are held from rotation relative to the member which it is desired to hold from rotation relative to the shaft. In this case this member consists of the housing to which I have given the general reference numeral 20. This housing is provided with the laterally extending flange 29 which is designed to house the friction disc members mentioned and which is notched at 30 to receive extending lugs 25 from the discs 26, whereby the discs 26 illustrated in Figures 8 and 9, may be held from rotation relative to the housing 20. As these discs 26 are alternated it will be seen that a pressure tending to press the two sets of discs together will tend to hold the housing 20 from rotation relative to the pinion 19, and thereby the shaft 16. This pressure is accomplished in two ways, one of which will hereinafter be described, and the other of which is a normally constant urge caused by providing the washer 32 illustrated in Figures 10 and 11 with the roll as is illustrated particularly in Figure 10, and then placing this washer 32 within the housing 20 which yieldingly holds the clutch discs 26 in engagement at all times. The rear end of the housing 20 is provided with longitudinally extending spirally curved fingers 33 which have their rear ends 110 at the outer edges bevelled somewhat at 34, as illustrated in Figure 13. A collar 35 is keyed at 36 and also fastened by a pin 37 to the rear end of the shaft 16. This pin 37 passes thru the shaft 16 and collar 35 and may 115 be held in place, if desired, by having its ends perforated to permit the passage of the retaining wire 38 as is illustrated in the drawings. This collar 35 is provided with forwardly extending spirally curved fingers 39 120 which interlace with the fingers 33 on the housing 20 and form a close fit therewith. Now, it will be seen that if the housing 20 rotates relative to the collar 35 then that the spiral throw given by the fingers 33 and 39 125 will tend to move the housing 20 longitudinally along the shaft 16; rotation thereof will cause pinion movement in either direction. The throw of these fingers 33 and 39 is such that when the starting motor 15 ro- 130

tates the shaft 16 in its normal direction then that the housing 20 and pinion 19 will be moved longitudinally along the shaft 16 to position to engage the teeth 14 on the fly wheel 13. This movement will, therefore, tend to force the chamfered ends of the teeth 23 and the pinion 19 past the correspondingly chamfered ends of the teeth 14 until the end of the pinion 19 engages with the end 10 of the nose, which occurs only when the teeth 14 and 23 are fully engaged. This engagement will flatten the washer 31 due to the throw of the interlacing spiral fingers 33 and 39 thereby forcing the clutch discs 26 into close engagement with each other to thereby hold the pinion 19 from movement relative to the housing 20. It will, therefore, be seen that from the time the edges of the teeth 23 engage the teeth 14 until the teeth mentioned 15 are fully in engagement then that the friction clutch member will permit rotation of the pinion 19 relative to the housing 20 which will be resisted only by the pressure of the washer 32 which tends to hold these friction 20 clutch members together. As soon, however, as the respective teeth are fully in engagement then the throw of these cam fingers forces the clutch discs into engagement which causes the fly wheel to rotate with 25 the pinion 19. If, however, the engine should for any reason backfire, then the friction clutch members 26 have sufficient slippage to allow the pinion 19 to rotate in a direction opposite that in which it is urged to 30 rotate by the motor 15 until the effect of the backfiring has been dissipated. In this connection it may be mentioned that during the course of a long series of experiments with the device here illustrated I have been enabled to backfire an engine many hundreds of times when the pinion 19 was in engagement with the fly wheel without damaging the engaging device appreciably.

As has heretofore been mentioned, the ends 35 of the fingers 33 are chamfered or bevelled at 34. Spaced somewhat from these bevelled or chamfered portions 34 are channels 61 illustrated in Figure 13. The fingers 39 are provided with smaller or complementary channels 62 so that when the cam fingers 33 and 39 are in their contracted position then there will be a continuous annular channel extending around the cylinder formed by these interlaced fingers. Mounted in this annular channel thus formed is a resilient ring 63 designed to have sufficient resiliency to tend to hold it in the channel thus formed. The rear edge of the channel formed in the members 33 is slightly bevelled. It will, therefore, be seen that when the starting motor is actuated the cam fingers will so act as to pull away from each other thereby pulling the ring 63 out of the channel 61 over the bevelled edge of the channel 61 so that the pinion 19 may come into operative position relative

to the teeth 14. When the engine starts the throw of the pinion will be reversed and the fingers will again engage throughout their entire length which will cause the chamfered portion 34 to slide under the ring 63 which will allow the ring 63 to ride over the fingers 33 until the ring reaches the channels 61 into which it will drop. This ring 63 will, therefore, hold the fingers in full engagement and prevent the pinion 19 from engaging teeth 14 due to any accidental movement of the pinion along the shaft 16 which would normally occur in connection with the use of this engaging device. This locking device is considered one of the most important features 75 of my invention as it keeps the pinion 19 normally out of engagement with the teeth 14 thereby preventing undue wear of the parts. My experiments have shown, however, that it does not appreciably interfere with the throwing in or the throwing out of the gear when the latter should be engaged or disengaged.

Among the many advantages arising from the use of my improved device, it may be specifically pointed out that I have provided an engagement between a starting motor and an engine which solves, to a large extent, the problems with which I am familiar, and which have arisen in connection with engagements of a similar nature. In the first place the engaging device provided operates automatically. It is also so constructed that it will withstand back-firing of the engine for a large number of times and in fact will withstand more of such usage than would occur in connection with ten times the life of any ordinary internal combustion engine. The mechanism also provides a driving connection which gives 105 a torque directly proportionate to the torque of the starting motor so that there is always a sufficiently positive drive between the starting motor and the engine to rotate the engine from the starting motor. Moreover, 110 it will be noted that the complete device may be readily assembled upon the starting motor shaft by simply sliding it over the shaft in position where the Woodruff key 36 will engage the sleeve 35 which will automatically throw the openings in the starter shaft and sleeve 35 in position where the pin 37 may be passed therethru to provide a further locking engagement which will take care of all end thrusts of the engaging device and part of the torque thereof. I prefer, however, to so construct the device that the Woodruff key 36 will largely take care of the torque.

If it is desired to disassemble the device from the starter shaft it is only necessary to un-twist the wire 38, pull it out from the ends of the pin 37, and then allow the pin 37 to drop out which will permit the engaging device to be slid off the shaft longitudi-

nally. After the engaging device has been disassembled from the shaft it is possible to disassemble the gear 19 from the device and with it the clutch portion thereof by simply un-twisting the wire 60 which will permit the screws 27 to be loosened so that the gear 19 may be withdrawn and thereby permit access to, or removal, of the clutch portion of the device. It will, therefore, be seen that I have provided a structure, which may be readily assembled or disassembled, of unitary formation, and which is not at all likely to get out of order; and, if for any reason it should get out of order, then that it may be easily repaired.

I have also provided means for automatically engaging the longitudinally movable portion of my improved device for locking it in inoperative position, so that it will not accidentally become engaged with the teeth on the fly wheel. Even, however, assuming that such engagement should occur, it will be seen that the clutch members will slip as there will be no pressure caused by the torque of the starting motor to force these clutch members together to form a positive connection between the gear 19 and the shaft 16.

Some changes may be made in the arrangement and construction of the various parts of my improved device without departing from the spirit of the invention disclosed therein, and it is my intention to cover by my claims such changes as may be reasonably included within the scope thereof.

I claim as my invention:

1. In a device of the character described, a starting motor having a shaft extended

therefrom, a sleeve secured to said shaft, a second sleeve floated on said shaft, an engaging device floated on said shaft, means for operatively connecting said second sleeve with the engaging device adapted to form a driving connection which will permit unlimited slippage therebetween when a maximum load has been placed thereon, and means for connecting said first and second sleeves whereby movement of the shaft combined with inertia of the parts associated with the second sleeve will cause movement of said second sleeve and the parts associated therewith longitudinally of said shaft.

2. In a device of the character described, a starter motor having a shaft extended therefrom, a sleeve fixed to said shaft, a second sleeve floated on said shaft, an engaging device floated on said shaft, means for operatively connecting the first and second sleeves whereby imparting rotation to the shaft will cause the float sleeve to move longitudinally relative to the shaft, means for operatively connecting the engaging device and said floating sleeve whereby the engaging device is normally held from rotation relative to the second sleeve by a relatively light resistance, said first mentioned means being adapted to increase said resistance automatically to the torque capacity of the motor when the sleeve and engaging device have reached a predetermined position, said means permitting slippage when the torque capacity of the motor is exceeded.

Dated May 1, 1922.

JAMES R. QUINLAN.
